UNITED STATES PATENT OFFICE.

THOMAS KEITH, OF NEW YORK, N. Y.

ELEVATING APPARATUS.

SPECIFICATION forming part of Letters Patent No. 297,696, dated April 29, 1884.

Application filed February 16, 1884. (No model.)

To all whom it may concern:

Be it known that I, THOMAS KEITH, of the city and county of New York, in the State of New York, have invented a new and useful 5 Improvement in Elevating Apparatus, of which the following is a specification.

My invention is more particularly intended for raising or lowering freight or goods in the form of barrels, boxes, bags, bales, or other 10 parcels or packages; but it may be embodied in a passenger-elevator.

The invention relates to that class of elevators or elevating apparatus which comprises two endless chains or wire ropes mounted on 15 chain or driving wheels at the top and bottom of the hoistway, and connected by cross-rods, so as to form, in effect, a continuously-operating carrier. In such an elevator or elevating apparatus the packages of goods are 20 placed, preferably while the endless carrier is moving, upon platforms or moving tables on the carrier, and, after being raised or lowered the required distance, are deposited on a floor 25 above or below that from which they were taken, as the case may be.

My invention consists in various novel combinations of parts and details of construction, hereinafter described, and pointed out in the claims.

30 In the accompanying drawings, Figures 1 and 2 are sectional elevations of an apparatus embodying my invention. Fig. 3 is an irregular horizontal section on the line $x-x$; Fig. 1; and Figs. 4 and 5 are sectional elevations of 35 a passenger car or cab to be used with my elevator if designed for passenger traffic instead of freight.

Similar letters of reference designate corresponding parts in all the figures.

40 A A' A² designate the three floors of a building in which my elevating apparatus is arranged. The hoistway or frame-work is formed, principally, by four uprights or posts, B, which are arranged two on a side, and are 45 held in fixed relation to each other by being securely bolted to the floor-beams a, and to horizontal sleepers or timbers a', placed on each floor. The posts B at each side of the hoistway are also connected by cross-timbers 50 b' b' b².

C designates a shaft which extends horizontally across the hoistway, and which is supported in bearings on the cross-piece b.

Above the shaft C is a driving-shaft, C', which is geared with the shaft C by a spur-wheel, c, and pinion c', and on which are fast and loose pulleys c' c'', for a driving-belt. The shaft C' is supported in bearings on the cross-piece b', and by it a rotary motion in the direction of the arrow, Fig. 2, is imparted to 60 the shaft C.

Upon the shaft C are two sprocket or chain driving-wheels, d d, and at the top of the hoistway are similar wheels or idlers, e e, which are in the same planes as the wheels d d, and 65 from each of which a short shaft, e', projects outward, and is supported in a bearing, e''.

At the outer end of each shaft e' is a collar, e³, which bears against the outer end of the bearing e'' and prevents the inward movement 70 of the wheel. By these means the wheels e e are kept in the same plane as the wheels d d.

D designates two endless-chains, which run over the wheels d e, the chains being driven by the wheels d and forming the endless and 75 continuously-operating carrier of the apparatus. The chains may be made of malleable iron or other links, and they and the chain-wheels are so formed and adapted to each other that they will not slip on the wheels. 80 The links of the chains are pivoted together, and are provided with inwardly-projecting ears, e⁴, which overlap opposite sides of the rims of the chain-wheels, and so prevent the chains from shifting laterally on the wheels. 85

In connection with the chains D are employed two pairs of guides, f f', which are held in proper relation to each other by brackets f² on the posts B, and the purpose of which I will hereinafter explain. The vertical portions of the guide f' are joined at the bottom by semicircular portions f³, and at their upper ends by semicircular frames f⁴, which may be of cast-iron. On these frames f⁴ are erected the standards f⁵, which support the bearings e² of 90 the upper chain-wheels e; and whenever it is desired to tighten the chains D D, the frames f⁴, standards f⁵, and bearings e² may be raised bodily by means of adjusting-screws f⁶.

The moving platforms or tables E are here 100

represented as four in number, and each is supported and connected with the chains D in the following simple manner:

g designates rods or cross-bars, which extend between and are connected at their ends with the chains, and the ends of these rods or bars are designed to run or travel between the guides f of the two pairs. The ends of said rods g will preferably be provided with friction-rollers to reduce friction.

From each rod g, near its ends and inside the chains, depend hangers or links g', which at their lower ends are connected with and support a cross-rod, g'', which is provided at the ends with rollers working in the guides f'. The hangers or links g' are set so as to just clear the chain-wheels e e and pass between them, as shown in Fig. 1. Consequently it will be understood that in whatever position the hangers or links of each pair may be they will always hang vertically, and their lower ends will be held in proper position by the engagement of the rod g'' with the guides f'. The semicircular guide portions f' f'' are of the same or near the same radius as the chain-wheels d e, and consequently as the rods g are being carried around the upper or lower chain-wheels the rods g'' will be passing through the guide portions f' f'' and will always be held vertically.

From the rod g'' arms g''' extend outward and slightly upward, and to the outer ends of these arms, at*, is pivoted the platform E. The said platform is slightly lower at the middle of its width and slants from each side downward to the center. The center of the platform is directly over and rests upon the rod g'', and the weight is thus supported in the same plane as that in which the chains move. The arms g''' may be considered as part of the hangers g'.

The form of the moving platforms E and the manner of supporting them from the chains are very desirable. They are of such shape that the load, when it consists of a round bale or barrel, cannot roll off, and yet can be readily delivered or unloaded, when the platform is moving downward, by raising its inner edge and tilting it on the pivots *. The center of gravity of the load always falls in the plane of movement of the chains, and hence a comparatively heavy load may be carried with little friction and wear of the guides.

Inasmuch as the resting-point of the platform E on the rod g'' is below the pivots *, there is no danger of the platform being accidentally tilted, and it will maintain its horizontal position while making the complete circuit of the chains, or until it reaches the point where it is desired to deliver.

I will now describe how the load is taken onto the platform automatically as the platform is rising.

Each of the floors A A' A'' is cut away at the side on which the chains ascend, so as to afford space for a loading-platform, F, which

is pivoted at h, and below said platform is a rock-shaft, i, which may be turned slightly by means of a handle or lever, i', and which, by means of short arms i'', carries a tripper-plate, 70 i''', pivotally connected with said arms. A link or rod, i'', extends from the rear edge of the tripper i''' to the loading-platform F forward of its pivots h, and consequently when the rear edge of the tripper i''' is depressed the 75 front edge of the loading-platform will be correspondingly depressed, and said platform will be tilted to such an extent that its load will roll off. By means of the lever i' the tripper i''' may be moved away from the chains, 80 as shown in the case of the floors A' A'', so that the moving platform E, in ascending, will not touch the tripper; but, when desired, by reversing the handle or lever, the tripper may be moved forward or toward the chains, as 85 shown in the case of the floor A, so that the moving platform, in ascending, will strike it.

On the platform F at the lower floor, A, is a barrel, G, which is to be loaded, and by pulling the lever i' back the tripper i''' has been 90 thrown forward. As the moving platform E, which is at the bottom of the hoistway, comes into the position shown in Fig. 2 by dotted lines, its edge strikes the under side of the front edge of the tripper i''' and tilts said tripper from a horizontal position into the position shown by dotted lines. The tilting of the tripper i''' produces a reverse tilting movement of the loading-platform F, which is sufficient to cause the barrel G or other package 100 of goods to roll or slide from the loading-platform F onto the moving platform E, and the latter having passed the tripper i''', the loading-platform drops back into its normal position. The loaded platform E, in rising, clears 105 all the trippers i''' which are above the floor at which it received its load, and by the movement of the chains is carried over to the descending side of the apparatus.

At each floor A' A'' is a delivery-tripper or tripping device consisting of a rock-shaft, j, provided between the chains with arms j' and at its ends with arms j''. The trippers in Fig. 2 are both shown as in an inoperative position, the rock-shafts j being so turned that the arms j' are out of reach of the inner edges of the platforms E. When it is desired to deliver at the floor A', the delivery-tripper at that floor will be swung into the position shown in dotted lines in Fig. 2, and will be retained in such 110 position by reason of its arms j'' striking against stop-pins j'''. (Shown in Figs. 1 and 2.) When the delivery-tripper at the floor A' is swung into such a position that its arms j' project in the path of the moving platform E, it 115 is retained in such position by reason of its arms j'' coming against the under side of the cross-timber b'', as shown by dotted lines in Fig. 2. As the moving platform E descends, its inner edge comes against the arms j' of the delivery-tripper, and is thereby tilted on its 120 pivots * into the position shown in Fig. 2 by

dotted lines, and the platform is thus tilted far enough to allow its barrel or package G' to roll or slide off the moving platform. As soon as the load is discharged, the moving platform drops back into its horizontal and normal position.

On the inner sides of the hangers or links g' are stop-pins s, which preclude the moving platforms E from being tilted too far or unnecessarily far in delivering their load.

H designates a double partition, which extends vertically midway between the ascending and descending portions of the chains.

In order to prevent any accident by reason of either of the chains breaking, I secure to each of the four posts B a stop, l, and a stop, m, which are respectively pivoted at l' and m'. The stop l will yield to an upward movement of the chain, but will not yield to a downward movement; but the stop m yields to a downward movement of the chain and against an upward movement of the chain. The stop m will be blocked by reason of the projection m' abutting against the post or upright.

In Figs. 4 and 5 I have illustrated the method of connecting a passenger cab or car with the chains. The rod g is connected with the chains, as before described, and the pendent hangers g' are bolted to the sides of the car, as shown.

The rod g' connects the hangers or links g' below the car or cab. The rod g will be guided by the guide f, and the rod g' will be guided in the guide f'.

In a passenger-elevator the chains would have to be stopped to take on and let off passengers, as in other passenger-elevators, and there can be no occurrence of injury to passengers by the car or cab striking the top of the building, as sometimes occurs in ordinary elevators in case of breakage of rope.

The elevator car or cab constitutes a moving platform for passengers.

In lieu of chains D D, wire rope might be used, the form of the wheels d d e e being suitably modified.

What I claim as my invention, and desire to secure by Letters Patent, is—

1. In an elevating apparatus, the combination, with two endless chains or carriers and wheels therefor, arranged at the top and bottom of the apparatus, of a rod extending between and connected with said chains or carriers, hangers depending from said rod between the chains or carriers, a moving platform pivoted to and carried by said hangers, and a tripping mechanism against which the inner edge of said platform is brought in its descent to tilt said platform and cause it to deliver its load outward, substantially as herein described.

2. In an elevating apparatus, the combination, with two endless chains or carriers and wheels therefor, arranged at the top and bottom of the apparatus, of a moving platform depending by means of hangers from and between the chains or carriers, guides for the

chains or carriers, and independent guides for the lower portions of said hangers, whereby the vertical position of said hangers is continuously maintained, substantially as herein described.

3. In an elevating apparatus, the combination, with two endless chains or carriers and wheels therefor, arranged at top and bottom of the apparatus, of a rod extending between and connected with said chains or carriers, hangers depending from said rod, a moving platform pivoted to and suspended by said hangers, pivoted loading-platforms capable of being tilted by the moving platform in its ascent to deliver their load upon the moving platform, and a trip mechanism for tilting said pivoted moving platform independently of its hangers in its descent in order to deliver the load, substantially as herein described.

4. In an elevating apparatus, the combination, with endless chains or carriers and a cross-rod connecting them, of hangers depending from said rod, a moving platform pivoted to said hangers, and pivoted loading-platforms capable of being tilted by the moving platform in its ascent to depress the inner edges of said loading-platforms and cause their load to pass onto the said moving platform, substantially as herein described.

5. In an elevating apparatus, the combination, with two endless chains or carriers and a cross-rod extending between and connecting them, of hangers depending from said rod between the chains or carriers and provided with outwardly-extending arms, and a moving platform slanting from opposite edges toward its center, pivoted to said outwardly-extending arms of the hangers at a distance from its center, and supported by said hangers at its center, substantially as herein described.

6. The combination, with endless chains and wheels therefor, of a rod, g, extending between said chains, hangers g', a rod, g', connecting the lower ends of said hangers, arms g', extending outward and upward from the rod g', and a moving platform having its lowest point at the center, pivoted to said arms, and resting upon the rod g', substantially as herein described.

7. The combination of the wheels d e, endless chains D D, the rods g g', the hangers g', and arms g', separate guides for the ends of said rods g g', and the moving platform E, pivoted to the arms g' and resting on the rod g', substantially as herein described.

8. The combination, with two endless chains or carriers and wheels therefor, of moving platforms depending by means of hangers from and between said chains or carriers, a pivoted loading-platform, a tripper pivoted below said loading-platform and within range of said moving platform in its ascent, and a rod or connection between the rear end of said tripper and the front end of said loading-platform, whereby the moving platform, in rising, will act upon said tripper, and by raising its front

end will depress the front end of said loading-platform and cause it to deliver its load upon the moving platform, substantially as herein described.

5 9. The combination, with endless chains or carriers and a moving platform suspended between them, of a pivoted loading-platform, F, the shaft i , the lever i' , whereby said shaft may be turned, the arms i'' , the tripper i''' , pivoted to said arms, and the rod i^4 , connecting the tripper in rear of its pivot with the platform F forward of its pivot, substantially as herein described.

10 10. In an elevating apparatus, the combination, with two endless chains or carriers and

cross-rod connecting them, of hangers depending from said cross-rod between said chains or carriers, movable platforms suspended by said hangers and capable of making the complete circuit of the chains or carriers without being inverted, guides for said chains or carriers, and stops applied to the chains or carriers, capable of yielding to the forward movement thereof, but serving to prevent a reverse movement, substantially as herein described. 20 25
